UNITED STATES PATENT OFFICE.

JULIUS STANLEY WAGNER, OF KEMMERER, WYOMING.

LOCK.

Application filed November 23, 1923. Serial No. 676,588.

To all whom it may concern:

Be it known that I, JULIUS STANLEY WAGNER, a citizen of the United States, and a resident of Kemmerer, in the county of Lincoln and State of Wyoming, have invented certain new and useful Improvements in Locks, of which the following is a specification.

This invention relates to locks and has 10 for its object the provision of a simple, efficient and structurally strong device.

Another object of the invention is the provision of a lock presenting the appearance of a simple barrel closed at opposite ends 15 and with a swingable shackle locked in position by a bolt actuated to locked position by a powerful spring.

A further object of the invention is the provision of a spirally threaded key adapted 20 to engage cooperating internal threads in a bolt for withdrawing the keeper to release the usual swingable shackle when it is desired to disengage the lock from the usual staples mounted upon the elements forming 25 the closure to a chamber.

This invention will be best understood from a consideration of the following detailed description, in view of the accompanying drawing forming a part of the 30 specification; nevertheless it is to be understood that the invention is not confined to the disclosure, being susceptible of such changes and modifications which shall define no material departure from the salient features of the invention as expressed in the 35 appended claim.

In the drawings:

Figure 1 is a view in perspective of my improved lock applied to a closure.

40 Figure 2 is a longitudinal vertical section of the same with the lock in open position.

Figure 3 is a longitudinal vertical section of the lock showing the bolt in closed position.

45 Figure 4 is an end view of the lock.

Figure 5 is a transverse vertical section of the lock taken along the line 5—5 of Figure 3.

50 Figure 6 is a longitudinal vertical section of the key for releasing the bolt of the lock.

Figure 7 is an end view of the key shown in Figure 6.

Referring more particularly to the drawings, 1 designates a cylindrical barrel having one end closed by a plug or disc 2 and a ring 3 rigidly mounted in the opposite

end of the barrel and through which is slidably mounted a cylindrical bolt 4. The main body of the bolt is spaced from the inner wall of the barrel 1 and is provided 60 with an annular shoulder or enlargement 5 having its periphery in engagement and slidable on the inner wall of the barrel.

A coil spring 6 is located between the main body portion of the bolt 4 and the inner wall of the barrel 1 and has one end in engagement with the enlargement 5 and its other end abutting the ring 3. A cylindrical lug 7 projects laterally from the enlargement 5 of the bolt and is mounted eccentrically on the outer face of said enlargement.

The outer wall of the barrel is provided with a pair of upstanding ears 8 between which is pivotally mounted at 9 a swingable 75 shackle 10. The free end of the shackle is adapted to be inserted through an opening 11 in the wall of the barrel and is provided with a perforation 12 through which the lug 7 is inserted when the shackle is locked in 80 position and when the bolt has been released by a key which will be presently described.

The bolt 4 is provided with a central bore 13 having internal threads 14. The inner end of the bore 13 is provided with a 85 threaded passage into which is screwed the threaded end of a pin 15 which extends longitudinally and centrally of the bore and terminates at the outer end of the bolt 4.

A cylindrical key 16 has external threads 90 17 adapted to mesh with the internal threads 14 of the bore 13. The key is provided with a central longitudinal passage 18 for receiving the pin 15. Formed integrally with the key 16 is a cup-shaped member 19 having an internal diameter of sufficient breadth to receive the outer end of the bolt 4 when said bolt is forced outwardly by the key, the end 20 of the cup-shaped member being adapted to engage the ring 3 in 95 the barrel 1. A handle 21 is provided at the rear of the cup-shaped member 19 for operating the key 16.

The lock is shown applied to any form of closure with a base plate 22 secured to 105 one portion of the closure while a base plate 23 is secured to the other member of the closure. A staple 24 projects laterally from the base plate 22 and is rigidly connected therewith. A staple 25 is rigidly 110 connected with the base plate 23 and is adapted to align with staple 24 when the

elements of the closure are in position for receiving the swingable shackle 10.

The operation of my device is as follows:

5 In Figure 3 the bolt 4 is normally located within the barrel 1 with the lug 7 inserted within the perforation 12 in the free end of the swingable shackle 10 whereby said shackle is locked in position. The 10 spring 6 forces the bolt 4 normally within the barrel 1 and therefore maintains the lug 7 in engagement with the passage in the swingable shackle hasp 10. A block 26 mounted upon the inner wall of the barrel 1 and diametrically opposite to the passage 11 in said barrel is adapted to limit the inward movement of the bolt 4.

When it is desired to release the lug 7 from the passage 12 in the swingable 20 shackle, the key 16 is inserted within the threaded bore of the bolt 4 and rotated through the handle 21. The inner end 20 of the cup-shaped member 19 resting upon the ring 3 maintains the key from longitudinal 25 movement and therefore causes the bolt 4 to be withdrawn as the threads 17 of the key mesh with the internal threads 14 of the bore 13. When the bolt has been sufficiently withdrawn and the lug 7 released 30 from the perforation 12 in the swingable shackle, said shackle may be withdrawn.

The pin 15 slides within the passage 18 in the key when the bolt 4 is withdrawn from the barrel. The pin 15 mounted centrally 35 of the bore of the bolt 4 is adapted to prevent the insertion of any form of rotatable means having threads of proper

pitch to engage the internal threads of the bore to prevent unauthorized withdrawal of the bolt from the shackle.

What I claim is:

A lock comprising a hollow barrel, a bolt 40 slidably mounted in said barrel and provided with an internally threaded bore and a shoulder at one end, a pin rigidly mounted in the inner end of the bolt and projecting centrally through the bore, a ring mounted at one end of the barrel, a coil spring embracing the bolt and having one end in engagement with the ring and its other end 45 in engagement with the shoulder on the bolt, a shackle pivotally mounted on the barrel at one end and provided with a perforation at its free end, said barrel being provided with a passage to which the free 50 end of the shackle is adapted to be inserted, a lug on the inner end of the bolt and adapted to be forced into the perforation in the free end of the shackle by the spring, means on the inner end of the barrel adapted to limit the inward movement of the bolt, means enclosing one end 55 of the barrel, a key provided with a bore adapted to receive the pin in the bolt, threads on the key adapted to mesh with the internal threads on the bore of the bolt, and a cap on the outer end of the key having a peripheral flange adapted to engage the ring in the barrel and cooperating with the intermeshing threads of the key and the internal threads of the bolt for causing withdrawal of the bolt when the key is rotated.

JULIUS STANLEY WAGNER.
